UNITED STATES PATENT OFFICE.

WALTER SCHAFER, OF BERLIN, GERMANY, ASSIGNOR TO GESELLSCHAFT FÜR DRAHTLOSE TELEGRAPHIE M. B. H. HALLESCHES, OF BERLIN, GERMANY, A CORPORATION OF GERMANY.

AMPLIFIER.

Application filed November 16, 1922, Serial No. 601,260, and in Germany November 19, 1921.

In low frequency amplifying circuit arrangements when it is desired to effect large amplification and a plurality of tubes are, therefore, used, self-oscillations are likely to 5 occur in the amplifying arrangement.

It is an object of this invention to provide an arrangement in which self-oscillations are either entirely prevented or much decreased.

In the drawing,

10 Fig. 1 is a diagrammatic representation of a circuit arrangement embodying the invention and,

Fig. 2 illustrates a further embodiment of the invention.

15 In Fig. 1 of the accompanying drawing 1 is an amplifying tube which has an output e. g. of 1 kw. The anode is supplied with current from the battery 2, and the amplified output is taken off at 3. The battery 4 supplies the necessary grid potential for the 20 tube 1, and the small tube 5 is connected in the grid circuit of the tube 1 so as to act as a resistance.

When the current to be amplified is transmitted to the grid of the tube 5 through the transformer 6, then alternately positive and negative potential occurs at the grid of the tube 5 whereby the resistance of the tube 5 and therefore also the potential supplied 30 from battery 4 to the grid of the tube 1 are rhythmically varied. One of the advantages of such circuit arrangement consists in that there are no transformers between the tubes 5 and 1, these tubes causing the usual internal oscillations and singing of the arrangements. Furthermore, the present circuit arrangement has the advantage that the resistance variations in the tube 5 have the full effect, and there is no output loss in the controlling 35 tube 5, which would be unattainable if transformers were inserted between the tubes.

40 As is well known, it is profitable to provide in amplifying arrangements tubes connected in opposition to each other. In such opposing circuits the disturbing noises caused by heating or inequalities in the anode potential are balanced. Such an opposing arrangement is shown in Fig. 2, the circuit arrangement shown in Fig. 1 being used with it. The current to be amplified is transmitted to the 45 transformers 6, and the amplified output is taken off from transformer 3. It should be noted that in the arrangement shown in Fig. 1 as well as in the arrangement shown in Fig. 50 2, the current for heating the tubes 5 must be

electrically insulated from the current sources 2 and 4 as well as from the current for heating the tubes 1. For such arrangements alternating current heating is particularly applicable, separate transformers being used for 50 each tube. The heat transformers are provided with secondary windings independent of each other, and their primary windings are connected in series or in parallel. Obviously in the arrangements shown in Figs. 1 and 2 instead of the individual tubes 1 a plurality of such tubes may be provided in parallel. The same thing holds good also for the tubes 5.

55 In the same manner as they are useful for low frequency amplification, the circuit arrangements represented in the drawings may also be employed for high frequency amplification. In this case, instead of the transformers 6 and 3, circuits are used that are 75 tuned to the frequency to be amplified.

The tubes 1 and 5 may be interconnected in manners differing from that shown without departing from the principles of the invention, so long as the manner comes fairly 80 within the scope of the appended claims.

Having described my invention, what I claim is:

1. An amplifying arrangement comprising a first amplifying tube having a filament, 85 grid and plate, and a second amplifying tube having a filament, grid and plate, the filament of said second mentioned tube being connected to the grid of said first tube and the plate of said second tube being connected to 90 the filament of said first tube, and a source of potential connected between the filament of said first tube and the plate of said second tube.

95 2. An amplifying arrangement comprising a first three electrode tube, a second three electrode tube, means connected between the filament and grid of said second tube for impressing thereon the electrical oscillations to be amplified, the filament and plate of said second tube being connected to the grid and filament respectively of said first mentioned tube whereby the amplified oscillations are impressed upon said first mentioned tube and further amplified thereby, and a source of potential connected between the filament of said first tube and the plate of said second tube.

105 3. An amplifying arrangement comprising a first set of amplifying tubes connected in 110

- opposition to each other in parallel circuits, a source of current common to said circuits, a second set of amplifying tubes, the filament and plate of each of said second set of tubes being connected to the grid and filament respectively of separate tubes of said first set of tubes, said second set of tubes being arranged to vary the resistance of the grid circuits of said first set of tubes in accordance with the energy to be amplified, and a separate source of current in the grid circuits of the first set of tubes for applying potential to the grids, said sets each constituting a stage of amplification.
- 15 4. An amplifying arrangement comprising a first set of amplifying tubes connected in opposition to each other in parallel circuits, a source of current common to said circuits, a second set of amplifying tubes, the filament and plate of each of said second set of tubes being connected to the grid and fila-

ment respectively of separate tubes of said first set of tubes; said first set of tubes being arranged to vary the resistance of the grid circuits in accordance with the energy to be amplified and means for applying potential to the grids of the first set of tubes, said sets each constituting a stage of amplification. 25

5. An amplifying arrangement, comprising, a first set of amplifying tubes having their cathodes connected together, a second set of amplifying tubes having their anodes connected together, the cathode of each tube of the second set being connected to the grid of a tube of said first set, a source of energy between said connected cathodes and connected anodes for supplying anode current to said second set of tubes, and means for supplying said second set of tubes with the energy to be amplified. 30 35
